UNITED STATES PATENT OFFICE

PIERRE ARBEIT, OF PARIS, FRANCE, ASSIGNOR TO THE HARTFORD-EMPIRE COMPANY,
OF HARTFORD, CONNECTICUT, A CORPORATION OF DELAWARE

MANUFACTURE OF GLASSWARE

Application filed April 21, 1926, Serial No. 103,426, and in France May 1, 1925.

This application discloses improvements upon the machine for making glassware described and claimed in my copending application for Letters Patent, filed April 24, 1925, 5 Serial No. 25,574. The present application has for its object certain improvements in machines for automatically manufacturing bottles or analogous glass articles such as flasks, jars, carboys and the like, described 10 in my said copending application. These improvements relate to:

First, a mechanism for opening the finishing molds characterized in that these molds, disposed in alignment upon the longitudinal 15 axis of the machine, are opened and closed in a vertical plane perpendicular to this longitudinal axis by moving pivotally about a horizontal axis, while the parison molds, in their opening and closing movements, move 20 pivotally around a vertical axis located behind the vertical plane in which the opening of the finishing molds takes place. This arrangement permits mounting a very great number of molds on the machine without increasing the width of the machine and consequently without making it necessary to have a glass-gathering opening of large dimensions.

Second, the provision of a scraper in front 30 of the parison molds for displacing the glass which has been chilled by the preceding gathering operation from the place where the new gathering is to occur.

Third, an arrangement permitting the entire machine to be lowered vertically when the parison molds enter the furnace, so as to lower these molds vertically upon the glass and to plunge them into the glass to exactly the same extent and so that the filling of the 40 molds will be assured when suction is produced. These different mechanisms are pneumatically controlled.

Fourth, a safety mechanism which automatically draws the machine back in the 45 event that a stoppage takes place for any rea-

son at the time when the molds are in the furnace, thereby avoiding putting the molds out of service, and also the mechanism located at the front of the machine, as a result of prolonged exposure to the temperature of 50 the furnace.

In the accompanying drawings:

Figure 1 is a side elevational view, with parts in section, of the mechanism for opening the finishing molds;

Fig. 2 is an end view of the same structure as seen from the left of Fig. 1;

Fig. 3 is a side elevational view, with parts in section, showing the scraper mechanism in front of the parison molds, and its operating mechanism;

Figs. 4 and 5 are views in elevation and in plan, respectively, of a modified construction of the scraper;

Fig. 6 is a somewhat diagrammatic view 65 of the arrangement serving to lower and raise vertically the machine as a whole;

Fig. 7 is a somewhat diagrammatic view of the safety device serving automatically to draw the machine backward; and

Fig. 8 is a fragmentary plan view of a part 70 of the structure shown in Fig. 1, showing the relation of the two sets of molds when the final blow molds are closed and the blank molds open.

As shown in Figs. 1 and 2, the finishing molds *a* are disposed in alignment along the longitudinal axial plane of the machine in front of the parison molds *b* when the machine is at rest. These parison molds *b*, in their opening and closing movements, pivot around a hinge or vertical axis *b*¹. These movements are controlled, as described in my above-mentioned prior application, by a compressed air cylinder *c*¹ fixed on the slide 80 *c* and having a piston *c*² which, through its piston rod *c*³ actuates links *c*⁴ to cause the opening and closing of the parison molds *b*.

The opening and closing movements of the finishing molds *a* are controlled by a 90

compressed air cylinder d disposed vertically and provided with a piston d^1 , the rod d^2 of which is T-shaped and is connected to two small links d^3, d^4 which are connected respectively to cranks d^5, d^6 which are respectively fixed to a hollow shaft d^7 and to a shaft d^8 passing through the hollow shaft d^7 . These shafts transmit angular movements of rotation in opposite directions to levers d^9, d^{10} connected to the carriers a^1, a^2 of the finishing molds a . In accordance with the direction of displacement of the piston d^1 in the cylinder d , the levers d^9 and d^{10} cause the halves of the molds a to separate or to approach each other, thus producing the opening or the closing of these molds. The opening or closing movement is thus produced in the vertical plane perpendicular to the plane in which the molds a are aligned, that is to say, the axial longitudinal plane of the machine, by pivoting around the horizontal axis of the concentric shafts d^7 and d^8 . The admission of compressed air into the cylinder d , and its escape from this cylinder, are regulated by bleeder valves d^{11} which enable the desired speed of operation to be obtained with certainty and without shocks.

The arrangement of the finishing molds described above permits the disposal along the longitudinal axis of the machine of a large number of molds without increasing the width of the machine, and thus permits reducing to a minimum the width of the gathering openings.

The slide c carrying the parison molds b moves horizontally and its movements are controlled by a compressed air cylinder (not shown) in the same manner as is described in my above-mentioned prior application. It is guided in its movements by two rollers, one of which, c^5 , is secured on the slide, while the other roller c^6 is mounted on the fixed frame e of the machine.

As shown in Fig. 3, the slide c carries, at its forward end, a scraper f disposed in front of the parison moulds b and intended, when the slide enters the furnace or gathering pool, to move aside the glass which has been chilled by the preceding gathering operation from the place where the new gathering is to occur.

When the slide c advances, that is to say, is moved to the left in Fig. 3, and has passed over the wall of the furnace or gathering pool, the valve g disposed on the cylinder c^1 which accompanies the slide c in its movements, is opened by coming in contact with the fixed rail e^1 carried by a part of the frame e of the machine. A dog g^1 pivoted on the stem of the valve g strikes the rail e^1 and thus causes this valve stem to descend. The air which is under pressure in the cylinder c^1 is admitted through the pipe g^2 behind the piston g^3 of the cylinder g^4 which may be formed integral with the slide c . This piston g^3 is pushed to the left and acts through the rod

g^5 connected to the bell crank f^1 pivoted on the slide c to cause the bell crank f^1 to rock. This bell crank f^1 carries the scraper f which descends more or less deeply into the glass according to the adjustment of the stop screw f^2 which limits the angular movement of the bell crank f^1 . The scraper f moves aside the glass which has been chilled by the preceding gathering operation. When the slide c arrives at the end of its forward movement, the dog g^1 of the valve g escapes from the rail e^1 and the valve g again closes. The air behind the piston g^3 escapes from the cylinder g^4 by the pipe g^2 and the grooved portion of the valve stem g . The spring g^6 brings back the piston g^3 into its initial position and lifts the scraper f . During the return movement of the slide c toward the right, as seen on Fig. 3, the scraper is not operative, the dog g^1 being lowered by engagement with the rail e^1 , by pivoting around its point of articulation upon the valve stem g . It would obviously be possible to skim the glass during the rearward movement of the slide c . For this purpose it would only be necessary to turn the dog g^1 on the valve stem through 180° about the vertical axis of the stem.

The scraper f may be made of any suitable material. For example, it may be made of metal and may be cooled by circulation of water, or it may be made of refractory material. Likewise, this scraper may have a straight working surface or a curved surface and it may be arranged perpendicular with respect to the axis of the machine, or at any suitable angle, as shown in Figs. 4 and 5 at f^3 . This latter arrangement has for its object the setting up in the glass of a transverse current, which brings to the parison molds for each new gathering operation a portion of fresh glass which has not been touched by preceding gathering operations.

Fig. 6 shows the arrangement serving to vertically lower the machine as a whole when the parison molds enter the furnace. Since these molds are disposed in alignment on the axis of the machine, it is necessary that they descend vertically upon the surface of the glass in the gathering pool, so as to dip into the glass exactly to the same extent and to be filled when suction is applied.

For this purpose the frame e of the machine rests upon two arms h and i which are secured to the axles of the wheels h^1 and i^1 that support the machine, the wheels themselves being mounted loosely on their axles. A compressed air cylinder j disposed at the back of the frame e actuates by its piston j^1 , the rod j^2 of which is connected to the arm i to raise and lower the machine. The arms h and i are provided with branch arms h^2, i^2 of the same length, both connected by the coupling link h^3 which causes the two feet e^2 of the frame to move parallel to each other. A

counterweight h^4 (or a system of springs not shown) acting through the arm h , keeps the machine counterbalanced. The rod j^2 carries a stop screw j^3 which strikes the fixed abutment j^4 , which is integral with the frame e , 5 at the end of the movement of the piston j^1 and thus permits the descending movement of the machine to be regulated. At the back of the machine is likewise disposed a cylinder k containing a piston k^1 connected directly 10 by the rod k^2 to the axle of the rear wheels i^1 . This piston k^1 serves to raise the machine.

The operation of this structure is as follows:

When the parison molds b carried by the slide C arrive above the gathering point at the end of their movement, the abutment c^7 carried by the slide c opens the valve e^8 that is mounted at the front of the frame e . The air which 20 is under pressure in the conduit l passes through the cut-away portion of the stem of this valve e^8 through the pipe l^1 and is admitted through the bleeder valve j^5 above the piston j^1 into the cylinder j . This air under 25 pressure pushes the piston j^1 downward and turns the arm i , thereby lowering the machine. This movement is transmitted to the axle of the front wheels through the levers and links i^2 , h^3 , h^2 , so that the machine descends vertically, the slide c remaining horizontal. The air above the piston k^1 in the 30 cylinder k escapes through the bleeder valve k^8 , the conduit k^4 , the distributor m and the conduit m^2 .

When the piston j^1 , during its descent, uncovers the port n , the air passes more or less rapidly through the conduit n^1 according to the degree of opening of the valve n^2 which controls this conduit, and fills a reservoir e^4 .

When the pressure has become sufficient in this reservoir e^4 , a flexible diaphragm e^5 , associated with this reservoir opens a valve e^6 and the air held under pressure in the conduit l^2 passes through this valve e^6 into the conduit 45 l^3 and pushes the piston o^1 of the distributor o toward the left. At the same time, the air under pressure is admitted through the conduit l^4 behind the piston m^1 of the distributor m and pushes this piston m^1 toward the left. The air under pressure in the conduit 50

o^2 then traverses the distributor o , arrives at the distributor m through the conduit o^3 and, passing through the conduit k^4 and the bleeder valve k^8 , arrives above the piston k^1 in the 55 cylinder k . The piston k^1 descends, thus again lifting the machine. The air contained in the cylinder j escapes through the bleeder valve j^5 , the conduit l^1 and the cut-away portion of the valve e^8 after this valve has resumed its initial position as a result of the return movement of the machine.

The time of gathering the glass by the parison molds b is regulated by the greater or less opening of the valve n^2 in the conduit 65 n^1 between the cylinder j and the reservoir e^4 .

Fig. 7 shows the safety arrangement which automatically pulls back the machine in the event that a stoppage takes place in the functioning of the machine when the parison molds are in the furnace.

A casing p , which protects the parts of the machine that are the most exposed to the heat, is connected to a conduit p^1 for supplying water under pressure and is also connected to a conduit p^2 for discharging this cooling 70 water. Through this conduit p^2 the water returns to a cylinder q through which it passes in front of the piston q^1 and thence escapes through the conduit p^3 provided with a valve p^4 . The piston q^1 is connected 75 to the frame e of the machine by its rod q^2 . The cylinder q is held in a fixed position by a support r fixed on the rails of the machine.

The degree of opening of the valve p^4 is 80 regulated in such a way that during normal operation the cooling water from the casing p reaches a temperature of about 90° C. In the event that, through an accidental stoppage, the molds b remain in the furnace, the 85 water contained in the casing p is brought to the temperature of vaporization and the valve p^4 is not sufficient for the passage of the steam thus produced. The pressure of this steam acts on the piston q^1 and pushes 90 it toward the right, which causes the machine to move back on its rails, the wheels h^1 and i^1 thereby reaching the position shown in dot-and-dash lines, and consequently the molds b are moved out of the 95 furnace. A safety valve q^5 permits the regulation of the pressure of the steam by means of the counter-weight q^4 adjustable on the operating lever q^6 of the valve, and prevents the steam pressure from exceeding 100 the pressure of the water entering through the feed pipe p^1 .

Priority under the International Convention for the Protection of Industrial Property of March 20, 1883, is claimed for the present 110 application by reason of the filing in France on May 1, 1925, of a corresponding application for a French patent of addition, No. 30,446, application No. 19,840.

I claim as my invention:

1. In a machine for automatically manufacturing bottles and other like articles, an arrangement for opening the finishing molds, characterized in that these molds, disposed in alignment along the longitudinal axis of the machine, are opened and closed in a vertical plane perpendicular to this longitudinal axis by pivoting around a horizontal axis, while the parison molds, in their opening and closing movements, pivot around a vertical axis 120 located behind the vertical plane in which the opening of the finishing molds takes place.

2. A glass working machine comprising a plurality of split finishing molds arranged 125 in alignment, means for opening and closing

said finishing molds by pivotal movement around a horizontal axis displaced vertically from said finishing molds, a like number of suction-fed split parison molds, and means for opening and closing said parison molds by pivotal movement around a vertical axis displaced longitudinally with respect to said finishing molds.

3. A glass working machine comprising a plurality of split finishing molds arranged in alignment, supports for the corresponding halves of the said finishing molds, and means for moving said supports to open and close said finishing molds by pivotal movement around a horizontal axis displaced vertically from said molds, said means comprising a fluid pressure cylinder, a piston rod, concentric shafts carrying said supports, levers carried by said shaft and links connecting said piston rod to said levers for causing said shafts to rock equally in opposite directions in response to movement of said piston rod.

4. A glass working machine comprising a suction-fed parison mold, means for advancing and retracting said mold toward and away from a charging position above a body of molten glass, a scraper moving with said mold for skimming the glass and for thereby providing a fresh surface of glass for engagement by said mold, and means for lowering said scraper to engage the glass during one movement of said mold and for holding said scraper above the glass during the opposite movement of said mold.

35. A glass working machine comprising a suction-fed parison mold, means for advancing and retracting said mold toward and away from a charging position above a body of molten glass, a scraper moving ahead of said mold in its movement toward the charging position, and means for actuating said scraper and arranged to lower said scraper to engage the glass during the advancing movement of said mold, and for raising the scraper and holding it above the glass during the retracting movement of said mold.

6. A glass working machine comprising a suction-fed parison mold, means for advancing and retracting said mold toward and away from a charging position above a body of molten glass, a scraper moving ahead of said mold in its movement toward the charging position, and means for actuating said scraper and arranged to lower said scraper to engage the glass during the advancing movement of said mold, and to raise the scraper and hold it above the glass during the retracting movement of said mold, the said actuating means comprising a pivotal mounting for said scraper, a fluid pressure cylinder connected to rock said scraper about its pivot, a spring tending to hold said scraper in a position raised above the level of the glass, and means for alternately admitting pressure fluid to said cylinder and for exhausting pressure fluid therefrom.

7. A glass working machine comprising a suction-fed parison mold, means for advancing and retracting said mold toward and away from a charging position above a body of molten glass, and a scraper moving with said mold for skimming the glass and for thereby providing a fresh surface of glass for engagement by said mold, said scraper having a working surface inclined with respect to the line of movement of said mold, so as to displace the surface of the glass both forwardly and laterally.

8. A glass working machine comprising a carriage, a plurality of suction-fed parison molds and a like number of finishing molds mounted on said carriage, means for moving said parison molds simultaneously to a charging position above a body of molten glass and for thereafter retracting said molds away from the charging position, and means for lowering said carriage bodily when said molds are above the glass so as to lower said molds and immerse their ends equally in the glass.

9. A glass working machine comprising a carriage, a suction-fed parison mold and a finishing mold mounted on said carriage, means for moving said mold to a charging position above a body of molten glass, and means operable automatically in the event that said parison mold remains in the heated environment of the molten glass longer than a predetermined time, for bodily moving said carriage away from the glass and for thereby removing the said parison mold from the charging position.

10. A glass working machine comprising a carriage, a suction-fed parison mold and a finishing mold mounted on said carriage, means for moving said parison mold into and out of a furnace containing molten glass, a casing mounted for movement with said parison mold, means for circulating cooling liquid through said casing, and means for bodily withdrawing said carriage away from said furnace in the event that said parison mold remains in said furnace beyond a predetermined time, the said withdrawing means comprising a stationary fluid pressure cylinder, a piston within said cylinder and having its piston rod connected to said carriage, means for conducting the cooling fluid from said casing past the side of said piston toward said carriage, and a valve for regulating the flow of liquid past said piston.

11. A glass working machine comprising a carriage, a parison mold and a finishing mold mounted on said carriage, means for moving said parison mold to and away from charging position above a body of molten glass, means for lowering said carriage bodily when said parison mold is above the molten glass, so as to bring said mold into contact with the glass, the last named means including a pair of operating cylinders respectively for lowering and raising said carriage, delay action

means responsive to movement of the piston in said lowering cylinder for admitting pressure to said raising cylinder, and means to vary the speed of action of said delay action means.

5 12. Glass working apparatus comprising a container for molten glass, a suction-fed parison mold, means for repeatedly presenting said mold to the glass in said container, a skimming device operating in timed relation with the movements of said parison mold for skimming the surface of glass in said container to provide a fresh surface of glass for each engagement by said mold, said skimming device being mounted to reciprocate toward and from the outer edge of said container, and means for moving said skimming device in a closed path such that the locus of a point thereof which is adapted to contact with the glass comprises a four-sided figure in a vertical plane and includes a lowering movement adjacent to the outer edge of said container and a raising movement at the inner part of its path.

25 13. A glass working apparatus comprising a container for molten glass, a suction-fed parison mold, means for repeatedly presenting said mold to the glass in said container, a skimming device operating in timed relation to the movements of said parison mold for skimming the glass in said container to provide a fresh surface of glass for each engagement by said mold, said skimming device being mounted to reciprocate toward and from the outer edge of said container, and means to control the position of said device during said movement in a manner such that the path of movement of said device in one direction is lower than the return path.

40 14. Glass working apparatus comprising a container for molten glass, a suction-fed parison mold, means for repeatedly presenting said mold to the glass in said container, a skimming device operating in timed relation to the movements of said parison mold for skimming the glass in said container to provide a fresh surface of glass for each engagement by said mold, said skimming device being mounted to reciprocate toward and from the outer edge of said container, means to reciprocate said skimming device, and means to raise said skimming device adjacent to one end of its reciprocatory movement and lower it adjacent to the other end.

55 15. Glass working apparatus comprising a container for molten glass, a suction-fed parison mold, means for repeatedly presenting said mold to the glass in said container, a skimming device operating in timed relation to the movements of said parison mold for skimming the glass in said container to provide a fresh surface of glass for each engagement by said mold, said skimming device being mounted to reciprocate toward and from the outer edge of said container, means to

reciprocate said skimming device, and means to lower said skimming device adjacent to the outer edge of said container and raise it adjacent to the end of its reciprocatory movement distant from the outer edge of said container.

Signed at Paris, this ninth day of April, 1926.
